(57) **CLAIM**

The ornamental design for a shopping cart, as shown and
described.

DESCRIPTION

FIG. 1 is a perspective view of the shopping cart showing
my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a portion indicated with
numeric 9 in FIG. 1;

FIG. 10 is a perspective view of the bag portion of the
shopping cart;

FIG. 11 is a perspective view of FIG. 10 from another angle;

FIG. 12 is a front elevational view of FIG. 10;

FIG. 13 is a rear elevational view of FIG. 10;

FIG. 14 is a left side elevational view of FIG. 10;

FIG. 15 is a right side elevational view of FIG. 10;

FIG. 16 is a top plan view of FIG. 10;

FIG. 17 is a bottom plan view of FIG. 10;

FIG. 18 is another perspective view of FIG. 10 shown in a
zipped-up position;

FIG. 19 is a perspective view of the shopping cart in an
assembled state with the zipper in an un-zipped position;
and,

FIG. 20 is a perspective view of the shopping cart in an
assembled state with the zipper in a zipped-up position.

The shopping cart and the bag are shown separated in some
figures to show aspects of the design that may not be
apparent in the other views.

The broken lines shown in the drawings represent portions
of the shopping cart and shopping cart bag that form no part
of the claimed design.

1 Claim, 20 Drawing Sheets
